UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed December 1, 1919. Serial No. 341,690.

This invention relates to hydrocarbon motors and particularly to mixture forming and heating means therefor.

Recent developments in this art have brought out what is termed a "combustion heater" and the suction type of such heaters provides for drawing a combustible mixture into the heater combustion chamber by the suction of the hydrocarbon motor to which 10 the device is connected.

The present invention may be said to be an improvement upon the means for supplying the combustible mixture to the combustion chamber of a heater of the above referred to type, and it consists generally of 15 novel means for withdrawing a portion of the mixture from the motor carburetor.

One of the objects of the present invention is to simplify and improve upon the 20 means for supplying a combustible mixture to a combustion heater of the suction type.

Another object of the invention is to provide automatic control of an improved character for a combustion heater of the suction 25 type.

Other objects of the invention will appear from the following description taken in connection with the drawings which form a part 30 of this specification, and in which—

Figure 1 is a vertical section through a device embodying this invention;

Figure 2 is a section approximately on the line 2—2 of Figure 1, looking towards the right;

Figures 3 and 4 are sections on the line 3—3 of Figure 1, looking towards the left as indicated by the arrows, parts in these figures being shown in different positions; and

Figure 5 is a section similar to Figure 1 showing a slightly modified part of the device.

Referring to the drawings, 10 indicates a motor cylinder block which may contain 45 one or more cylinders, and 11 is the intake passage of the motor which leads to the intake valves, not shown. A motor intake pipe or conduit 12 connects a carburetor 13 with the intake passage 11 and this conduit 12 is jacketed as at 14, this jacket forming a combustion chamber or heater 15 around a portion of the intake conduit. The inlet to the combustion chamber is at 16 and its outlet at 17 through a plug 18, this outlet 17 communicating with the interior of the con-

duit 12 so that the combustion chamber 15 is constantly subject to the suction or depression of said intake conduit. A spark plug 19, suitably connected with the motor ignition mechanism, is arranged in the combustion chamber 15 so that a spark is created to fire the charge therein.

The carburetor 13 has a throttle valve 20 for controlling the amount of mixture passing from the carburetor to the intake conduit 12. 60 The carburetor also has an air inlet 21 and a fuel supply well 22, which well is connected in the usual way to a float chamber which maintains the liquid fuel at a constant level. The construction of such float chamber is so well known that it is not deemed necessary to illustrate it in the drawings.

The liquid fuel feeds upwardly from the well 22 through a vertically movable sleeve 23 and through a tapered passage or channel 24 in a rod 25 which is vertically movable in the sleeve 23. The sleeve 23 is manually adjustable by a lever 26 which is connected by a small pinion (not shown) which meshes with a rack 27 on the sleeve. Suitable packing 28 prevents leakage of the fuel around the sleeve 23 to the rack 27 and pinion above referred to. Thus it will be seen that by oscillating the lever 26 the sleeve 23 may be moved downwardly or upwardly and thereby expose more or less of the tapered channel 24 in the rod 25 above referred to.

All of the above fuel feeding parts are supported by a portion of the carburetor which we term the guiding piece, lettered 29 in the drawings. This guiding piece has an upward extension 30, shown in Figures 1, 2, 3 and 4, and the rod 25 extends through and is guided by the upper part 31 of this upward extension. The piece 29 forms the lower wall of the carburetor and is secured to the body of the carburetor as shown by a series of screws 32 in Figures 2, 3 and 4. The upward extension 30 has a horizontal through passage of somewhat triangular form as shown at 33 in Figures 2, 3, and 4, with the apex of the triangle at the bottom. This passage 33 connects the air inlet of the carburetor with the outlet and the channel 24 opens into this passage at its lower part. Thus all of the air passing through the carburetor goes through the passage 33 and around the upper part of the channel 24 so that gasoline is drawn through the channel 24 into the air and mixed with it.

For the purpose of automatically controlling the mixture of gasoline, or other fuel, and air, both the gasoline channel 24 and the air passage 33 are simultaneously increased in size as the suction increases at the motor side of the carburetor. This is accomplished by a piston 34 arranged in a cylinder 35 mounted on top of the carburetor, which cylinder is connected by a passage 36 with the motor side of the carburetor, not, however, beyond the throttle valve 20. The piston 34 has a cylindrical skirt 37 which is guided on the exterior of the guiding piece 29 and which extends down into the air passage of the carburetor. This skirt surrounds the upward extension 30 of the piece 29 and it will be seen that as it is moved downward it gradually closes the air passage 33 in the carburetor. It is shown in half closed position in Figure 1, and the same in Figures 2 and 4. In Figure 3, however, it is near its lowest position. It will be seen that as the motor throttle 20 is opened and the speed of the motor thereby increased, the suction in the carburetor will increase and this suction will be communicated to the top of the piston 34 through the passage 36 and the piston will be thereby drawn upwardly to open wider the air passage 33. The rod 25, above referred to, is connected to the piston 34 as shown in the figures, and as the piston 34 is drawn upwardly the rod also moves and a deeper part of the fuel channel 24 is exposed to the passage of air through the carburetor. It is intended that the air passage 33 and the taper of the channel 24 shall be so proportioned relatively that approximately the correct mixture will be supplied to the motor at the various degrees of suction. For manual adjustment, however, the sleeve 23 may be moved to vary the relation between the depth of the channel 24 exposed and the amount of opening of the air passage 33.

It will be seen that with the throttle valve 22 in nearly closed position, as it would be in starting the motor, a relatively small suction will be created in the carburetor and the piston 34 will, therefore, be in its lower position, such as shown in Figure 3. Thus there will be a small air passage 33 due to the skirt 37 closing the greater part of it. The present invention contemplates arranging means in the lower part or apex of the passage 33 so that under the conditions above referred to a portion of the mixture may be readily withdrawn from the carburetor for feeding the combustion heater 15 hereinabove described.

This withdrawing means is shown in the form of a tube 38 mounted in the piece 29 and extending upwardly into the air passage 33. It is arranged at the outlet end of the air passage in the direct path of travel of mixture through the lower part of the

passage, and on its front side, that is the side exposed to the passing mixture, the tube 38 has a vertical slot 39 which will permit a given amount of the mixture to pass into the tube. The tube is connected by a pipe 40 with the inlet 16 of the combustion heater 15 so that the mixture which the tube 38 collects is led directly to the heater where the spark 19 fires it and thereby heats the walls of the intake conduit 12. It will be understood that the burnt gases pass through the outlet 17 into the conduit 12 where they further heat the mixture passing through the conduit.

With the tube 38 arranged in the lower part of the air passage 33, it will be seen that as the skirt 37 of the piston 34 is raised by the greater suction created as the throttle valve is opened, the passage 33 becomes very much larger and the greater part of the mixture passing through it will pass above the tube 38 and consequently the tube will collect a smaller proportion of the mixture. Also, as the throttle valve is opened, the suction at the carburetor and the suction in the combustion heater will become more nearly equalized so that there will be less tendency to draw mixture into the tube 38. Thus by both of these automatic controls the combustion heater operates at its full capacity when the throttle valve 20 is in closed or nearly closed position, but drops to its least capacity, or perhaps goes out entirely, when the throttle valve 20 is opened. In said open position of the throttle valve, it will be understood that usually the motor does not require that the mixture be heated because the greater speed of the mixture into the motor makes it burn more readily and it is not so necessary that it be heated. Moreover, the motor itself is then producing more heat and the exterior heat is not so desirable.

In the form of the invention shown in Figure 5, the mixture withdrawing device is in the form of a tube 48 having a slot 49 and a pipe 50 connects the tube 48 with the combustion heater as in Figure 1. In this form, however, the tube 48 is arranged on the opposite side of the skirt 37 from that shown in Figure 1. Thus the skirt in passing down alongside of the tube 48 is directly in front of the slot 49 and thereby closes off part of the slot when the skirt 37 is in its lowest position. This is illustrated in Figure 5, where the skirt is slightly below the top of the slot 49. In this figure the other parts of the carburetor are the same as in Figure 1. This form of the device gives a slight additional control by the skirt 37 so that a smaller amount of mixture is withdrawn by the device 48 when the suction in the carburetor is so low that the piston 34 is in its lowest position. This may be said to happen when the motor is idling and a little

less heat will be required for the combustion heater than when the motor is being started with the throttle partly open.

It will be understood that the forms shown herein are illustrative only of the invention, and various modifications thereof may be made without departing from the spirit or scope of the invention as defined by the claims.

10 Having thus described my invention, what I claim and desire to secure by Letters Patent is:—

1. In a carburetor, the combination with a horizontal mixture passage, a fuel inlet and a motor throttle, of means for withdrawing a portion of the mixture from the mixture passage, said means extending into the lower part of said passage between the fuel inlet and the throttle.

20 2. In a carburetor, the combination with a mixture passage and an adjustable fuel inlet, of a device for withdrawing a portion of the mixture from said passage arranged in the path of the fuel issuing from said fuel inlet.

30 3. In a carburetor having a throttle valve, the combination with a mixture passage adjustable independently of the throttle valve, and a simultaneously adjustable fuel inlet, of a device extending into said passage between the fuel inlet and the throttle valve for withdrawing a portion of the mixture from said passage.

35 4. In a carburetor, in combination, fuel and air inlets, means for withdrawing a portion of the mixture from the carburetor, and means for simultaneously controlling said fuel and air inlets and said withdrawing means.

40 5. In a carburetor, in combination, fuel and air inlets, means for withdrawing a portion of the mixture from the carburetor, and suction operated means for simultaneously controlling said fuel and air inlets and said withdrawing means.

45 6. In a carburetor, in combination, fuel and air inlets, means for withdrawing a portion of the mixture from the carburetor, and a suction operated piston for adjusting the fuel and air inlets and simultaneously controlling the withdrawing means.

50 7. In a carburetor, in combination, fuel and air inlets, means for withdrawing a portion of the mixture from the carburetor, said means being operated by the suction between the throttle and the motor cylinder, and means operated by the suction between the carburetor and the throttle for controlling the fuel inlet.

60 8. In a carburetor, in combination, fuel and air inlets, means for withdrawing a portion of the mixture from the carburetor, said means being operated by the suction between the throttle and the motor cylinder, and means operated by the suction between the

carburetor and the throttle for controlling the air inlet.

9. In a carburetor, in combination, fuel and air inlets, means for withdrawing a portion of the mixture from the carburetor, said means being operated by the suction between the throttle and the motor cylinder, and means operated by the suction between the carburetor and the throttle for controlling the fuel and air inlets.

10. In a carburetor, the combination with a mixture passage having an outlet tapered in transverse section, of a device for withdrawing a portion of the mixture arranged in the apex of said outlet.

11. In a carburetor, the combination with a mixture passage having an outlet tapered in cross section, of a device for withdrawing a portion of the mixture arranged in the apex of said outlet, and means for closing said outlet from its wider part towards its apex.

12. In a carburetor, the combination with a mixture passage having a throttle valve, a combustion heater having an outlet into said passage beyond the throttle valve whereby said valve controls the suction of the heater, means for supplying said combustion heater with mixture from said carburetor, and means subject to the suction between the carburetor and the throttle valve acting as an additional control of the heater supplying means.

13. In a carburetor, the combination with a mixture passage having a throttle valve, a combustion heater having an outlet into said passage beyond the throttle valve, means for supplying said combustion heater with mixture from said carburetor, and means subjecting to the suction between the carburetor and the throttle valve acting to relatively reduce the mixture to the heater as the throttle valve is opened.

14. A carburetor comprising a body portion, a guiding piece, a measuring fuel nozzle in the guiding piece, and a mixture outlet conduit separate from the main carburetor outlet mounted in said guiding piece.

15. A carburetor comprising a body portion, a guiding piece, a measuring fuel nozzle in the guiding piece, and a mixture outlet pipe extending into the carburetor and mounted in said guiding piece of the carburetor.

16. In a carburetor, the combination with a mixture passage and a fuel inlet thereto, of a motor throttle for the mixture, means extending into said passage for regulating its cross sectional area, and means arranged between said regulating means and said motor throttle for withdrawing a portion of the mixture from the carburetor.

17. In a carburetor, the combination with a mixture passage and an adjustable fuel inlet, of a device extending into the passage

beyond said inlet for regulating the cross sectional area of said passage, means extending into the passage beyond said regulating means and adapted to withdraw a portion 5 of the mixture from the passage, and a motor throttle arranged beyond said withdrawing means.

18. In a carburetor, in combination, fuel and air inlets, a suction operated piston for 10 adjusting the fuel and air inlets, and means for withdrawing a portion of the mixture from the carburetor, said means being arranged on the motor side of said piston.

19. In a carburetor, the combination with a horizontal mixture passage, of a device 15 extending into the passage from above for regulating its cross-sectional area, a combustion heater, and means beyond said regulating device for withdrawing a portion of the mixture from the lower part of the passage 20 and delivering it to said heater.

In testimony whereof I affix my signature.

MILTON TIBBETTS.
